UNITED STATES PATENT OFFICE.

ARTHUR HENROZ, OF BRUSSELS, BELGIUM.

APPARATUS FOR MAKING TILES.

1,192,630.

Specification of Letters Patent. Patented July 25, 1916.

Application filed July 2, 1913. Serial No. 777,033.

To all whom it may concern:

Be it known that I, ARTHUR HENROZ, manufacturer, a citizen of the Kingdom of Belgium, and resident of 335 Avenue Louise, 5 Brussels, Belgium, have invented certain new and useful Improvements in Apparatus for Making Tiles; and I do hereby declare the following to be a full, clear, and exact description of the invention, such as will enable others skilled in the art to which it appertains to make and use the same, reference being had to the accompanying drawings, and to letters or figures of reference marked thereon, which form a part of this 10 specification.

This invention relates to improvements in apparatus for the manufacture of patterned or fancy tiles, in which the tile under treatment is carried by a circular table having an 15 intermittent rotary motion to bring the tile successively opposite suitable devices for applying color, pressing the tile and other operations necessary for making the tile.

Hitherto in machines for manufacturing 20 patterned tiles, the colors were fed simultaneously through a stencil or patterned plate. According to the present invention, however, the tile is brought successively opposite a number of separate color feeding 25 devices, each of which sets the design in one particular color or material only, the tile being passed on by the rotation of the table to the further devices treating it. A greater 30 efficiency and accuracy of pattern is thereby obtained which is furthered by the improved 35 color distributing devices according to the present invention.

The invention is more particularly described with reference to the accompanying 40 drawings in which:

Figure 1 is a plan view of the whole apparatus. In this view some of the devices constituting the apparatus are in section. The part II is a section on O—P of Fig. 3. 45 The part III is a section on Q—R of Fig. 3, the part IV is a section on S—T of Fig. 2; Fig. 2 is a section on an enlarged scale on ABB' CC' of Fig. 1; Fig. 3 is a section on an enlarged scale on E—F of Fig. 1; Fig. 4 is a 50 section on an enlarged scale on G—H of Fig. 1; Fig. 5 is a section on an enlarged scale on M—N of Fig. 1. Fig. 6 illustrates the counter pattern.

A revolving plate composed of segments or 55 sections 1 supported by rollers 2 and 3 mounted on a frame 4, is provided with internal

teeth and is periodically rotated a certain distance by a toothed sector 5 driven by bevel gearing from the shaft 45. Each of these sections 1 has a rectangular aperture 60 in which is inserted a frame 7 carrying twin molds 6. Under this aperture a sliding member 8 adapted to be operated by a handle 9, is arranged. The intermittent rotation of the plate successively brings each pair of 65 molds 6 to the place where the operations for making the tiles are carried out, namely at I the placing of the pattern members or stencils which act as means to separate the various colors; at II, III, IV, V and VI, 70 the insertion of the various colors (the apparatus shown thus enables tiles to be made comprising five different colors not including the foundation or body color); at VII the stencil members are removed, at VIIbis, 75 the molds are filled up with body color (filling up mass) at VIII the tiles are pressed and, at VIIIbis, removed from the molds. The stencil members, withdrawn by hand at VII, are placed on a belt conveyer 10 which 80 brings them to I, ready to be used again. The molds thus provided at I with their stencils are brought to II and then successively to III, IV, V and VI. In each of these 85 positions, they are automatically fed with a differently colored material from a hopper 11 closed by two sliding doors 12 and 13. Each of these slides 12 and 13 is controlled mechanically, in such a way that when one 90 of them is opened the other is closed, and the result is, that when the upper slide 12 is open, the material falls on to the slide 13 and when the latter is subsequently opened, the quantity of material thus predetermined 95 lying between 12 and 13 falls on to a sieve 14. This sieve is fixed to a framework 15 which supports all the sieves and is itself carried by arms 16 on a vertical shaft 17; cams 18 and 19, operated by shaft 20, act alternately on the ends of the framework 15, 100 so as to impart to it an oscillatory motion which aids the sieving action. Springs arranged at 21 increase the oscillations producing counter oscillations. Beneath each 105 of these sieves a counter pattern 22 (Fig. 6) is arranged and is mechanically operated, so as to place itself above the mold (Fig. 3) before the coloring matter falls through the sieve, and to be then withdrawn and afterward to be turned (Fig. 2), so as to discharge into a suitable receptacle 23 the excess of colored material not utilized. This 110

movement of the counter pattern may be operated by any suitable mechanical combination. Figs. 2 and 4 show one of these possible combinations by way of example. Fig. 2 represents the parts when the counter pattern 22 has completely turned, at the moment when it is about to take up again its normal position. Fig. 4 represents the parts at the moment when the counter pattern is 10 completely drawn back and is about to begin to turn.

The counter pattern 22 is provided with two pivots 25, each sliding in a slotted member 26. These two pivots 25 pass through 15 the ends of a fork 28 hinged at 29 to a lever pivoted at 30. This lever carries at its end a cam slot 32, which engages a stud 31 fixed on a plate 33 rotated by a motor shaft 24. It is evident that the rotation of the 20 shaft 24 causes a displacement of the counter pattern from the position illustrated in Fig. 2 to that illustrated in Fig. 3 and vice versa. In order that the counter pattern may remain, during the time necessary for the 25 discharge of the material in the mold, in the position illustrated in Fig. 3, the cam slot 32 has a circular part concentric with the wheel 33.

The rotation of the counter pattern 22 at 30 the end of its path, which is necessary to discharge the excess of material into the receptacle 23, is obtained by the action of the rack 34 with which there engages a toothed wheel 27 keyed on one of the pivots 25, when 35 the counter pattern is completely drawn back toward the rear (Fig. 4). The rack 34 is fixed to a lever 35, which is movable around an axis 53 fixed to a support 56. A stud 36 fixed on the plate 33 at this moment 40 meets the lever 35. The rotation of the plate then causes the movement of the lever 35 around its pivot and thus lowers the rack 34. The movement continues till the stud 36 is no longer in contact with the lever 35 45 as shown in Fig. 2. The lever 35 thus becomes free when the rack 34, under the action of the spring 37, again takes up the position shown in Fig. 4 and places the counter pattern in its original position. The 50 stud 31 is displaced from the position represented in Fig. 4 to that in Fig. 2 in the circular part of the cam slot 32 and thus it has not caused a displacement of the lever pivoted at 30. The movement of this lever thus 55 only begins when the stud 31 has reached the end of the circular part of the cam slot 32 *i. e.* somewhat later than the position shown in Fig. 2.

In the modification shown in the drawing, 60 the shaft 24 also actuates the governing means of the sliding doors 12 and 13, which in this example consist of two rods 47 and 54 guided in supports 48 and operated by two arms 49 and 55 keyed on the shaft 50. 65 When the arm 49 leaves the rod 47, a spring

51 again moves the door 12 to its original position. One end of the spring 51 presses against one of the supports 48 and the other end against a projection 52 on the rod 47. The door 13 is operated in a similar manner. When the mold in question has successively received, in passing the points II, III, IV, V 70 and VI, the various colored materials (certain of which need not be used if the design does not contain them), it reaches the point VII where the stencil is removed by hand. The mold then passes beneath a bottomless trough 39 containing body (filling) material, the lower walls of which bear against the upper side of the revolving plate; a portion of this material then enters the mold and completes the filling of it. Portions of the colored material which may have been able to fall out around the mold during the foregoing operations are brought into this 80 mold by means of inclined plates 40. The mold thus completely filled is brought to the point VIII to the press 41, the successive operations of the various members of which are controlled by the usual cam members 42 on a continuously rotating shaft. Finally the pressed tile reaches VIIIbis; the slide piece 8 is drawn outwardly either by hand or 85 mechanically by means of a suitable mechanism (not shown) and the tile being no longer supported, falls by reason of its own weight or is ejected from the mold by the usual plunger mechanism 43 on to a conveyor 44 which carries it to the furnace or to the 90 drying apparatus, according to the nature of the materials employed. In order that these various operations may take place with precision, it is necessary to lock the revolving plate each time it has been moved a predetermined distance to bring a tile opposite a mechanism to operate upon it. For this object, locking members (not shown), controlled by the principal motor shaft 45, are 95 used, which enter notches 46 in the plate.

Claims:

1. In an apparatus for the automatic manufacture of patterned or fancy tiles, the combination of an intermittently revolving table carrying molds, a plurality of devices for filling said molds with color, each of said devices feeding one color only to the molds and being provided with a counter pattern sliding on the table, said counter pattern being moved away from the mold and reversed to empty it of superfluous material after colored material has been passed through it, mechanism for pressing the tiles, means for removing the tiles from the molds, means for bringing successively said molds opposite each of said filling devices, and means for feeding a determined amount of colored material to the counter pattern.

2. In an apparatus for the automatic manufacture of patterned or fancy tiles, the combination of an intermittently revolving

- table carrying molds, means for filling said molds with color, each of said means feeding one color only to the molds and being provided with a counter pattern sliding on 5 the table, means for moving said counter pattern away from the mold and reversing it to relieve it of superfluous material after colored material has been passed through it, means for pressing the tiles, means for re- 10 moving the tiles from the molds, means for bringing successively said molds opposite each of said machines, and hoppers on the means feeding the different colors to the molds provided with two sliding doors the upper one of which is open and then closed 15 before the lower door is opened.

In testimony whereof I affix my signature in presence of two witnesses.

ARTHUR HENROZ.
